CIRCUIT BREAKER

Albert B. Rypinski, Laurelton, N. Y., assignor to
 Metropolitan Device Corporation, Brooklyn,
 N. Y., a corporation of New York

Application May 16, 1940, Serial No. 335,488

6 Claims. (Cl. 200—88)

The invention herein disclosed relates to a relay or circuit breaker of the kind which while under normal conditions may be operated manually in the manner of an ordinary switch, operates automatically to open the circuit upon a continued overload or short circuit. More particularly, the invention relates to a relay or circuit breaker of the kind disclosed in the co-pending applications for patents, Serial Nos. 309,521 and 321,022, filed December 16, 1939, and February 27, 1940, respectively, which became Patent No. 2,260,583 on October 28, 1941, and Patent No. 2,336,036 on December 7, 1943, respectively.

In the aforesaid applications for patents there is disclosed a circuit breaker that primarily includes a case and two movable elements within the case, preferably rotatably mounted about a common axis and resiliently urged toward "off" position. The two elements comprise the primary operating parts and consist of a manually operative element or handle, and a switch element or rotor. Normally, when the handle is moved to the "on" position, it is releasably latched to the case in this position. The switch element normally moves to, and is positioned in, the "on" position with the handle as it is latched thereto through current-releasable latching means. On the existence of abnormal current conditions, the switch element is released from the handle and moves to "off" position and in so doing releases the handle which follows the switch element to "off" position.

An object of the present invention is to provide a circuit breaker of this kind in which the current-releasable means includes a coil mounted in the switch element. Another object is to provide a circuit breaker including a coil mounted in the switch element and means to obtain time delay in operation of the core or keeper upon which the coil acts. Another object of the invention is to provide a coil arranged to effect a more rapid release of the switch element upon the flow of exceptionally large currents. A further object of the invention is to increase the force effecting the release of the switch element with increases in current to secure a delayed action on slight overloads and a rapid action on short circuits.

These and other objects and certain advantages which will hereinafter appear are realized in the circuit breakers, illustrating by way of example, embodiments of the invention, that are disclosed in the accompanying drawings and described in detail below. The drawings include:

Fig. 1 which is a plan of a circuit breaker embodying the invention;

Fig. 2 which is a transverse section of the same taken on the line 2—2 of Fig. 1;

5 Fig. 3 which is a sectional side elevation taken on the line 3—3 of Fig. 1;

Fig. 4 which is a sectional side elevation taken on the line 4—4 of Fig. 1;

10 Fig. 5 which is a fragmentary sectional elevation of a modified form of switch element or rotor for the circuit breaker;

Fig. 6 which is a diagrammatic illustration of a modified arrangement of the circuit breaker illustrated in Figs. 1 to 4;

15 Fig. 7 which is a partial transverse section of a modified form of switch element for the circuit breaker;

Fig. 8 which is a sectional side elevation of the same taken on the line 8—8 of Fig. 7;

Fig. 9 which is a diagrammatic illustration of a modified arrangement of the circuit breaker illustrated in Figs. 7 and 8; and

20 Fig. 10 which is a transverse section of the modified form of circuit breaker illustrated diagrammatically in Fig. 9.

The several circuit breakers illustrated in the drawings essentially include a case and operating parts that are housed within the case. The case is the same for the several modified forms of the circuit breaker that are illustrated in the drawings, and, fundamentally, the operating parts are the same, the differences residing primarily in the mechanical and electrical arrangement for effecting a release of the circuit-controlling or switch element of the circuit breaker upon continued overload or short circuit. The case A for the circuit breaker is open at the bottom and has an opening 1 through the top for a finger piece 2 by means of which the circuit breaker may be manually actuated. A base B serves as a closure for the bottom of the case and as a support for stationary contacts 3 and 4, associated with connecting pieces 5 and 6 and terminals 7 and 8. The case and base together form a complete enclosure for the circuit breaker except for vents 9 and 10 extending vertically through the case to permit the free passage of gases generated by arcs formed within the case.

25 The operating mechanism in general includes two movable elements, a manually operative element or handle C from which the finger piece 2 extends, and a switch element or rotor D. The handle consists of a disk-like wall 11 from which a shaft 12 formed integral therewith extends. An axial flange 13 is formed at one portion of the

handle, the outer portion in the assembled circuit breaker, and extends from the wall 11. The finger piece 2 extends radially from this flange through the opening in the case. The rotor is partially encased within the handle and is rotatably mounted upon the shaft 12 which in turn is rotatably mounted in a slide 14 received in a complementary groove in one side wall of the case, and in the arcuate end of a slot 15 in the opposite side wall. A spring element acts upon the handle and rotor to effect independent movement thereof towards "off" or open-circuit position. This spring element consists of two torsional spring sections 16 and 17, one on each side of a central loop 18 extending substantially tangentially of the spring. The end of the spring section 16 is received in a groove or keyway in the shaft 12 and the end of the section 17 is received in a groove in the rotor. Under normal conditions, the handle, when removed to the "on" position, is restrained against the action of the spring section 16, which acts to urge the handle toward "off" position, by a latching lever 19 that enters in a recess 20 in the flange on the handle and engages the end wall of the recess. This lever is resiliently urged into latching relation with the end of the slot or recess 20 by the spring loop 18 which engages the latching end of the lever. The lever is pivoted between its ends upon a pivot pin 21 that extends from the slide 14 in which the shaft 12 is journaled. A cam surface 22 on the rotor is arranged to engage the end 23 of the lever when the rotor moves to "off" position. Upon engagement of the end of the lever by the cam surface 22, the lever is withdrawn from the recess in the handle and the handle is thus released to move to "off" position under the action of the spring section 16.

The rotor normally is latched, in a manner hereinafter described, to the handle so that when the handle is moved to "on" circuit position, the rotor moves with the handle. Likewise, the latching arrangement is such that if the handle be moved to "off" circuit position, the rotor under the action of the spring section 17 will follow the handle to the "off" position. The rotor carries contacts 24 and 25 which engage respectively, in the "on" position, with the stationary contacts 3 and 4. When the rotor moves to the "off" circuit position, the contacts 24 and 25 move away from the stationary contacts. Normally, the section 17 of the spring and the stationary contacts exert a force tending to rotate the rotor to the "off" position. The stationary contacts are mounted and arranged so as to have a certain amount of resiliency and are positioned with respect to the contacts on the rotor so that they are under tension in the "on" circuit position of the rotor.

The rotor is provided with current-releasable means for effecting the release of the rotor from the handle upon continued overloads or short circuit. It is with this current releasable means, as arranged in a circuit breaker of this kind, that the invention of this application is primarily concerned.

In the circuit breaker illustrated in Figs. 1 to 4, there is provided an electro-magnetic arrangement for releasing the rotor from the handle upon the existence of abnormal current conditions. The latching arrangement by which the rotor is normally secured to the handle includes a detent which consists of a dog-pointed, hardened set screw 26 that is threaded in an opening in the flange 13 and extends axially of the circuit

breaker. The end 27 of the set screw acts as a detent and is engaged, under normal conditions, by the shaped end 28 of a lever or keeper 29. The lever 29 is pivotally mounted upon a pin 30 extending between brackets 31, secured to the face of the rotor, and through brackets 32 formed on the lever. Embedded within the rotor there is a coil 33. One end of this coil is connected to the contact 24 and the other end is connected to the contact 25. A spring 34 coiled around the pin 30 acts upon the lever and normally biases it to a position in which the detent engaging end is held against the face of the rotor, in which position the end 28 engages the detent 27. By turning the set screw in the threaded opening in the handle, the extent of engagement between the lever and detent may be varied, and in consequence, the point at which the circuit breaker opens or the capacity of the circuit breaker may be varied or adjusted. Once set, the screw is preferably sealed against rotation. The engaging section or edge of the latch may be rounded to make a point contact with the detent and so minimize the drag on the lever when urged to the release position. The opposite edge 35 of the lever is preferably bent outwardly to form a lead-in.

It will be apparent that when the circuit breaker is closed, the current passing through the circuit passes through the coil 33. This coil is calibrated so that upon the passage of a particular current through it, the keeper 29 is actuated or drawn to the coil causing the engaging end 28 to be released from the detent 27. When this occurs, whether by virtue of a short circuit or a continued overload, the rotor is moved to the "off" position by the action of the spring section 17. Upon arriving at the "off" circuit position, the rotor, as previously described, trips the latching lever 19 and the handle follows the rotor to the "off" position. The lead-in on the latching lever permits the detent to pass the lever and since the circuit through the coil is broken, the lever will assume a position under the action of spring 34 in which it again engages the detent 27 when the handle is moved to the "on" position.

Fig. 5 shows a modified form of magnetic breaker with a dashpot in the rotor to delay the tripping in inverse proportion to the current. A shaft 36 carries all the rotating parts. The handle C' is cored out to form a cylinder 37 in which a piston 38 travels, with a spring 39 biasing it outwardly. This spring replaces the spring 34. When keeper 29 is attracted by coil 33 it presses piston 38 in against spring 39 and also compresses the air in cylinder 37. The air leaks around the shaft 36 and piston 38 finally allowing the latter to move in and permit the breaker to trip. The greater the magnetic pull on the keeper 29 the faster the air will be expelled and the more rapidly the keeper moves to unlatch position.

An alternative means for providing a time delay, in connection with the coil and keeper type breaker, is illustrated diagrammatically in Fig. 6. Here the coil 40 is shunted by a resistor 41 of high coefficient material. When current is at full load value it divides between the coil and resistor in such a proportion that the coil will not pull in its keeper 40' and the resistor is relatively cool. As the current rises above full load the resistor heats, increases in resistance, and the coil carries a proportionately larger percentage of the total current. At a predetermined critical value the keeper is attracted and the breaker trips. If the overload is of brief duration the 75 resistor does not have time to heat and a large

percentage of the total current passes through the resistor. The coil only gets a sufficient percentage to permit it to trip when the overload continues long enough to heat the resistor to a critical value.

Connected as indicated in the diagram, assuming a direct current supply, the current in the circuit will split in the inverse ratio of the resistance of the coil 40 and the resistor 41. With alternating current supply, the current split will be affected quantitatively by the inductance of the coil, but the net result will be the same as described below. Normally, the resistor may have a higher resistance than the coil so that the greater portion of the current passes through the coil. Under normal conditions, there will be little heating of the resistor, which may be made of nickel. However, upon increase of current passing through the circuit, heating of the resistor will occur depending upon the additional amount of current passing through the circuit. For example, if an overload occurs in which the amount of current passing through the circuit is double the rated capacity of the breaker, the greater portion of the current will pass through the coil. However, additional current will pass through the resistor, in fact twice the normal current will pass through the resistor. This additional current will effect the heating of the resistor. As it heats, its resistance becomes greater thus cutting down the amount of current that passes through it and increasing the amount of the current that passes through the coil. The relation of the resistor and coil may be such that upon a condition of this kind, i. e., a current of double the rated capacity, the breaker will trip after a period of two minutes. On the other hand, if a very heavy overload or a small short circuit occurs, causing a current over five or six times the rated capacity of the breaker, the amount of current that will pass through the coil will immediately cause the coil to trip the breaker and the heavier the current, the more rapid the tripping of the breaker will be. The keeper 40' may be a bimetal element as illustrated. In such case the action will be that, on slight overloads, the keeper will heat and warp to release the switch element. This action will be augmented by the coil as and in the manner described.

In Figs. 7 and 8, there is disclosed a modified form of the current-releasable means for the circuit breaker. In this form, the current-releasable latch is in the form of a bimetal element 42 substantially the shape of an inverted V. The ends of this bimetal element are secured to the contacts 43 and 44 on the rotor or switch element. Behind the bimetal element and embedded in the rotor, there is a conducting ring 45 in the shape of a washer. The bimetal element is spaced from this ring but is closely adjacent to the ring, with a small air gap between the ring and the bimetal element. The rivets 46 and 47 through which the bimetal element is secured to the contacts on the rotor and through which it is electrically connected to the contacts extend through insulated bushings, such as the bushing 48 extending through the ring 45. The arrangement of the bimetal and the ring is in the nature of a transformer.

The normal operation of the circuit breaker is by heating and warping, in the usual manner, of the bimetal element, and when warped the bimetal becomes released from the detent and releases the rotor. This heating and releasing of

the bimetal element is necessarily delayed in the case of a simple overload and should be very rapid in the case of a short circuit. When a heavy flow of current occurs through the bimetal, current is induced in the ring 45. If a heavy short circuit occurs, a relatively heavy current is induced in the ring. This current sets up its own magnetic field which causes a magnetic reaction well understood in transformer design and which results in repulsion between the bimetal element and the ring.

Power systems today are capable of supplying large short circuit currents and small circuit breakers for use on these systems are tested with 15 5000 ampere short circuits through them. An appreciable force is exerted between the bimetal and the ring when the bimetal is carrying a short circuit current of several thousand amperes. In consequence, the bimetal element is moved out of 20 latching engagement much more rapidly under short circuit conditions than it would by reason of heating and warping alone.

The ring 45 may be replaced by a coil that is connected across the bimetal element. This arrangement is illustrated diagrammatically in Fig. 9. The current passing through the circuit breaker will necessarily divide in accordance with the resistance of the bimetal element 42 and the coil 40.

30 This arrangement is illustrated in a circuit breaker in Fig. 10 of the drawings. This circuit breaker, in construction, is in all respects the same as that illustrated in Figs. 1 to 4 of the drawings, except for the construction and attachment of the bimetal element 42. In the construction of Fig. 10, the bimetal element 42 is positioned on, secured to the rotor and connected to the contacts 50 and 51 (Fig. 9) in the same manner as illustrated in Figs. 7 and 8. The coil 40 45 is preferably embedded in the rotor as illustrated and one end is electrically connected, as illustrated in Fig. 9, to one end of the bimetal and so to a switch element contact. The other end of the coil is electrically connected to the other switch contact and the other end of the bimetal. The operation of this breaker should be apparent from the previous description.

From the foregoing, it will be apparent that by 50 in the invention herein disclosed, there is provided in a circuit breaker of the kind referred to, an arrangement wherein a coil may be utilized to effectively release or assist in the release of the movable element of the circuit breaker. The arrangement is such that it permits the utilization of a circuit breaker construction that is comparatively simple and inexpensive. The arrangement provides a flexibility that may be utilized in securing a delayed action on slight overloads with a rapid action on heavy short circuits.

It will be obvious that various changes may be made by those skilled in the art in the details of the embodiments of the invention illustrated in the drawings and described in detail above within the principle and scope of the invention as expressed in the appended claims.

I claim:

1. In a circuit controlling device of the kind described, the combination comprising a movable switch element, a movable latch carried by the switch element acting as a releasable latch therefor, bias means to move the switch element upon releasing movement of said latch, and a coil carried by the switch element and inductively coupled with the latch for effecting relative re-

leasing movement of the latch with respect to the coil.

2. In a circuit controlling device of the kind described, the combination comprising a rotatably mounted switch element, a latch carried by the switch element and movable with respect thereto for acting as a releasable latch therefor, bias means for moving the switch element upon releasing movement of the latch, and a coil carried by the switch element, concentrically arranged with respect to the axis of rotation of the switch element and inductively coupled with respect to the latch.

3. In a circuit controlling device of the kind described, the combination comprising a movable switch element, spaced switch contacts carried by the switch element, a bimetallic latch carried by the switch element, connected across the switch contacts, movable with respect to the switch element, and acting as a releasable latch therefor, bias means to move the switch element upon releasing movement of the latch and a coil carried by the switch element and inductively coupled to the latch.

4. In a circuit controlling device of the kind described, the combination comprising a rotatably mounted switch element, spaced switch contacts carried by the switch element, a bimetallic latch carried by the switch element connected across the switch contacts, movable with respect to the switch element and acting as a releasable

latch therefor, bias means to move the switch element upon releasing movement of the latch, and a coil arranged concentrically with the axis of the switch element and inductively related to the latch.

5. In a circuit controlling device of the kind described, the combination comprising a movable switch element spaced switch contacts carried by the switch element, a bimetallic latch carried by the switch element, connected across the switch contacts movable with respect to the switch element, and acting as a releasable latch therefor, bias means to move the switch element upon releasing movement up of the latch, and a coil carried by the switch element, connected across the switch contacts and inductively related to the latch.

6. In a circuit controlling device of the kind described, the combination comprising rotatably mounted switch element, spaced switch contacts carried by the switch element, a bimetallic latch carried by the switch element connected across the switch contacts, movable with respect to the switch element and acting as a releasable latch therefor, bias means to move the switch element upon releasing movement of the latch, and a coil carried by the switch element, arranged about the axis thereof, connected across the switch contacts and inductively related to the latch.
